Attorney

UNITED STATES PATENT OFFICE

RUTH FREEDMAN, OF NEW YORK, N. Y.

LINGERIE FASTENER

Application filed August 16, 1929. Serial No. 386,314.

This invention relates to improvements in lingerie pins or shoulder strap attachments.

I have heretofore devised a lingerie pin for retaining the shoulder straps of undergarments and the like in proper position upon the shoulders, and the primary object of the present invention is to improve such shoulder strap attachments.

10 My prior attachment included an upper pin to be fastened to the inner surface of the shoulder portion of an outer garment, and a second or lower pin designed to form a supporting bar and retaining means for the shoulder straps of undergarments and the like. Another object of the present invention is to provide a shoulder strap attachment, the frame of which is of curved or crescent shape to facilitate the handling and manipulation 15 of the upper pin of the attachment.

Another object is to furnish an attachment of this character, in which the lower or second pin is specially shaped to prevent any pricking of the user's skin; to allow the operator to readily detect which is the free end 20 of the second pin, and to allow the shoulder straps to lie flatter than the pins heretofore used.

Another object is to provide the frame of 25 such attachments with a slight depression or cavity on the guard which engages the free ends of the pins, to allow the outer garment engaging pin to slip easily into the guard, and to stay in the latter until the user wishes 30 to detach the same from the outer garment.

With the foregoing objects outlined and 35 with other objects in view which will appear as the description proceeds, the invention consists in the novel features hereinafter described in detail, illustrated in the accompanying drawing, and more particularly pointed out in the appended claims.

Referring to the drawing,

Fig. 1 is a front elevation of my improved 40 shoulder strap attachment.

Fig. 2 is a rear elevation of the same, with both pins open.

Fig. 3 is a vertical sectional view on the 45 line 3—3 of Fig. 2.

In the drawing, 4 designates the frame of

my improved attachment, which is preferably formed of sheet metal, and is of crescent shape. The upper edge of the frame is thus curved from end to end, so that the central portion 5 of this edge is spaced below the pin 6 of the device when the latter is closed, while the ends of said pin are arranged considerably above the point 5. This provides a cut-out portion for the frame, so that the operator may readily grasp the medial portion of the pin 6 for the purpose of manipulating the latter.

The pin 6 is preferably formed of a piece of wire of circular cross section, and has a sharp point 7 that is designed to readily penetrate the shoulder seam of an outer garment, and to afterwards engage a guard lip 8 of the frame for securing the device to the outer garment, and protecting the point of the pin. The opposite end of the pin 6 is 50 preferably extended to form a cross bar 9 about which an end of the frame is curled for securing the pin member to the frame; and from the cross bar 9, the wire from which the pin element is formed, is preferably flattened or made of rectangular cross section to provide a strap retaining bar 11. The ends of this pin are offset rearwardly, as shown at 12 and 13, while the portion of the pin between these offset portions is arranged parallel to, but spaced from the rear surface of the frame, when the free end 14 of the strap retaining pin is interlocked with the guard lip 15 of the frame which cooperates with the end 14. The offsetting of the end 55 portions of the bar 11 properly space the main portion of that pin from the main portion of the frame, so that a plurality of shoulder straps may be placed over the bar 11, and be slidably retained by the latter when the parts 14 and 15 are interlocked.

The end 14 is blunt to prevent the same from sticking the wearer, and in order that the latter may readily operate the bar 11 by the sense of touch, that pin is provided 60 near the blunt end 14 with an indicator 16 which may be formed by distorting the wire into one or more U-shaped projections. Assuming that the pin 6 is closed, and retaining the shoulder straps in place, when the wearer 65

wishes to release the shoulder straps, the indicator 16 will readily indicate which end of the bar 11 may be loosened, even though the operator is unable to see the attachment.

5 As best shown in Fig. 3, a depression 17 is provided at the guard end of the frame, and the surface of this depression slopes toward the lip 8. This may be provided by forming a floral design or the like on the front face of the guard, and it allows the point of the pin 6 to slip easily into the guard, and causes it to stay there until the wearer wishes to remove the attachment for use on another garment.

15 In using the device, the operator will first insert the pin 6 through the shoulder seam of an outer garment from the inner side of the latter, and will then interlock the point 7 with the guard 8. Now, the retaining bar 11 is threaded beneath the shoulder straps, and then the blunt end 14 is interlocked with the lip 15. Obviously, the device functions to retain the shoulder straps in proper position, and at the same time, there 20 is enough clearance between the bar 11 and the frame 4 to permit the shoulder straps to slide relatively to the attachment and vice versa.

30 When the bar 11 is to be opened to cause detachment of the shoulder straps, the operator may readily find the proper end 14 of the bar instantly by placing a finger on the bar and moving the same along the latter until the crimp or indicator 16 is reached. 35 Then, by holding both ends of the frame between the forefinger and thumb, and by raising the shoulder straps a little with the same finger of the other hand, the lower bar will open instantly, and the shoulder straps may be slid off the same.

40 As before stated, when the pin 6 is to be manipulated, the curved upper edge 5 of the frame provides a cut-out to accommodate the forefinger and thumb of the hand, so that the pin 6 may be operated without interference by the frame.

45 The terms and expressions employed herein are used as terms of description and not of limitation, and there is no intention in the use of such terms and expressions, of excluding any mechanical equivalents of the features shown and described, or portions thereof, but it is recognized that various structural modifications are possible within the 50 scope of the invention claimed.

55 What I claim and desire to secure by Letters Patent is:

1. A lingerie fastener comprising a substantially crescent-shaped frame, and pin bars, each pin bar having one of its ends permanently secured to one end of the frame, and its opposite end detachably connected to the other end of the frame, one of said pins in closed position extending across the upper

edge of the frame and being spaced from the medial portion of the latter.

2. In a lingerie fastener, a frame having guards at one of its ends, pin bars, each having one of its ends permanently secured to the opposite end of the frame, and its free end detachably secured to one of said guards, the frame adjacent to one of said guards being provided with a depression to permit the point of one of the pin bars to slip easily 75 into its guard and to block accidental detachment of said point from the last mentioned guard.

3. A lingerie fastener including a frame and a plurality of pin bars, each bar having one of its ends permanently secured to the frame, and its other end detachably connected to the frame, one of said bars having its ends offset, and its medial portion extending substantially parallel to and in 85 spaced relation with the rear surface of the frame.

4. A lingerie fastener comprising a frame and a plurality of pin bars, each of said bars having one of its ends permanently secured to the frame, and its opposite end detachably secured to the frame, one of said bars having its ends offset and provided adjacent its 90 detachable end with an indicator.

5. A lingerie fastener comprising a frame, 95 a piece of wire having its medial portion permanently secured to the frame, the other portions of the wire forming pin bars, means for detachably connecting the free ends of the pin bars to the frame, one of said pin bars being pointed, and the free end of the other pin bar being blunt, and adapted to engage the shoulder straps of undergarments.

6. A lingerie fastener comprising a crescent-shaped frame, a piece of wire having its medial portion permanently connected to one end of said frame, the opposite end of the frame being provided with guards, the other portions of the wire forming pin bars, one of said pin bars having a pointed free end adapted to engage one of said guards, the last mentioned pin bar extending substantially straight across the frame with the major portion of the same arranged above and spaced from a curved edge of the frame, 115 the other pin bar having its ends offset rearwardly to space the major portion of that bar from the rear surface of the frame, the free end of the last mentioned bar being shaped to engage the other one of the guards 120 of the frame.

7. A lingerie fastener comprising a crescent-shaped frame, a piece of wire having its medial portion permanently connected to one end of said frame, the opposite end of the frame being provided with guards, the other portions of the wire forming pin bars, one of said pin bars having a pointed free end adapted to engage one of said guards, the last mentioned pin bar extending sub- 130

stantially straight across the frame with the major portion of the same arranged above and spaced from a curved edge of the frame, the other pin bar having its ends offset rearwardly to space the major portion of that bar from the rear surface of the frame, the free end of the last mentioned bar being shaped to engage the other one of the guards of the frame, the wire being crimped near 10 one of its ends to provide an indicator.
